UNITED STATES PATENT OFFICE

2,440,426

BRASSIÈRE

Miriam Cooper Barlow, Columbus, Ga., and
Everett Wayne Barlow, Sarasota, Fla.

Application November 29, 1946, Serial No. 712,900

4 Claims. (Cl. 2—42)

1

This invention relates to new and novel improvements in brassières. The conventional cloth brassière consists of one or more pieces of fabric suitable for covering and supporting the bust, held on the wearer by a back strap and shoulder straps. These straps confine the movements of the wearer and thus are detrimental to comfort, as well as to the wearer's appearance when outer low neck line clothing is worn. Further, the straps and connecting clasps are subject to breakage, must be repaired or replaced frequently and are difficult to launder.

Prior attempts have been made to avoid these disadvantages by various means, which means in some cases have allowed for the elimination of the shoulder straps. As a result of the present invention, however, a practical and attractive strapless brassière, requiring no clasps for attachment to the wearer, is afforded. The novel design of the invention in its several modifications and the more specific advantages thereof, will be more fully apparent from a description of the drawing, wherein:

Fig. 1 is a perspective view of one embodiment of the invention;

Fig. 2 is a side view of a woman shown wearing the invention of Fig. 1;

Fig. 3 is a perspective view of the wire brassière frame of the invention of Fig. 1;

Fig. 4 is a perspective detail of a removable fabric cover adapted to fit over the frame of Fig. 3; and

Figs. 5 and 6 are perspective views of two modifications of the invention.

Referring to Figs. 1—4, the invention illustrated consists of the resilient wire frame 10, which may be formed of a single piece of wire bent in the shape shown in Fig. 3 to form the curved upward ends 11, and the bust conforming curves 12. To provide additional strength, in the front, the ends of the wires forming frame 10 may be crossed and fastened as by a link 13, and crimped over the wire forming the lower part of frame 10, as at 14 and 15. As will be apparent hereinafter, the precise method of connecting the wire frame is not an essential feature of the invention, but may be accomplished in various ways without departing from the basis thereof.

As shown in Figs. 1, 2, and 4, the frame 10 is preferably covered with a removable envelope-like cover 16, having a slide fastener 17 along its lower inside edge permitting the frame 10 to be removed for the purpose of laundering or changing the cover 16. As illustrated, the cover 16 is of plain design, but obviously a variety of covers

2

suitable for various social occasions may be employed, and likewise the cover may be formed with pleats or other conventional bust supporting or molding features.

As shown in Figs. 1—3, the ends 11 of frame 10 provide the supporting means. These curve inwardly and upwardly, and terminate at points approximately opposite the horizontal center line of the bust conforming portion. Due to this construction, as seen in Fig. 2 frame 10 curves below the armpits and below and around the lower and inner edges of the shoulder blade, ends 11 curving upward to terminate at points along the inner edge of the shoulder blades, thus assuring a firm support for the bust supporting part of the brassière. The frame 10 and its upturned ends 11, being formed of resilient wire, may be bent to a considerable degree to conform to the figure of the particular wearer, and to assure the desired amount of grip of ends 11 around the body.

In Fig. 5 is illustrated a modified form of the invention, a brassière 20 of one-piece construction which may be formed of any suitable material having the desired resiliency, such as a plastic or sheet metal. Brassière 20 is formed in the same general shape as described above for the frame 10 with the upturned ends 11A. Depending upon the type of material employed, and the social occasion, brassière 20 may be employed with or without a fabric cover such as is shown in Fig. 3. For example, brassière 20 may be formed of an opaque plastic in colors to match the remainder of the costume and worn without such a fabric cover.

In Fig. 6 is illustrated another modified form of the invention, a brassière frame 30 of the same general description described for Fig. 5 except that it is formed with the open bust frames 31 and 40 requires a fabric covering such as shown in Fig. 3. This modification may likewise be formed of any suitable resilient material such as plastic or sheet metal.

The modifications of the invention as just described will be found to be very comfortable on the wearer, and depending upon the social occasion, these may be worn beneath other clothing, or as an outer garment for open midriff bathing suits, play suits, dresses and evening gowns. Likewise the provision of a removable cover, allows the same frame to be employed with a variety of covers suitable to various occasions. The invention further renders the use of elastic, straps, clasps and the like unnecessary, and greatly simplifies the laundering problem.

In the claims below the words "strapless brassière" will be understood to mean a brassière without supporting means over the shoulders, such as straps, and without back-joining or closing means, such as the usual elastic straps.

Having thus described the invention, what is claimed is:

1. In a strapless brassière, bust covering means including an integral framework of resilient material, the upper frontal portion thereof being disposed on the body above the horizontal mid-section of the bust, the lower frontal portion thereof being disposed on the body substantially directly beneath the bust and extending substantially laterally toward opposite sides of the body; said framework having body clasping end portions passing around opposite sides of the body beneath the armpits and extending to and exerting pressure against the back at separated points inside and between the shoulder blades of the wearer, said end portions providing the sole supporting means for the brassière.

2. In a strapless brassière, bust covering means including an integral framework of resilient material, the upper frontal portion thereof being disposed on the body above the horizontal mid-section of the bust, the lower frontal portion thereof being disposed on the body substantially directly beneath the bust and extending substantially laterally toward opposite sides of the body; said framework having body clasping end portions passing around opposite sides of the body beneath the armpits and extending to and exerting pressure against the back at separated points between the shoulder blades of the wearer approximately opposite the horizontal midsection of the frontal framework, said end portions providing the sole supporting means for the brassière.

3. In a strapless brassière, bust-covering means including an integral framework of resilient material, the frontal part of said framework being composed of an upper portion shaped in breast conforming loops resting against the body above the breasts and a lower portion disposed on the body substantially directly below the breasts and extending laterally toward opposite sides of the body; said framework having means to apply

supporting pressure against the back of the wearer consisting of integrally formed extensions of said upper and lower frontal portions, said extensions passing substantially laterally around the sides of the body beneath the armpits and in an upward direction to terminate at separated points inside and between the shoulder blades of the wearer, said extensions providing the sole supporting means for the framework; and a fabric cover for the breasts supported between said upper and lower frontal framework portions.

4. In a strapless brassière, bust covering means including an integral framework of resilient material, the frontal portion whereof substantially covers the breasts, the lower edge of said frontal portion being disposed on the body substantially directly below the breasts and extending substantially laterally toward opposite sides of the body; and extensions of said frontal framework passing around the sides of the body beneath the armpits and terminating at separated points inside of and between the shoulder blades of the wearer, and exerting pressure at said points to provide the sole supporting means for said framework.
